(57) **CLAIM**

The ornamental design for a ring floor lamp as shown and described.

DESCRIPTION

FIG. 1 is a front, top perspective view of a ring floor lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, front perspective view thereof;

FIG. 9 is a bottom, front perspective view thereof, showing the ring floor lamp in an open state of use;

FIG. 10 is an enlarged detail view taken from portion 10 of FIG. 3; and,

FIG. 11 is an enlarged detail view taken from portion 11 of FIG. 3.

The broken lines in the drawings depict portions of the ring floor lamp that form no part of the claimed design.
